VAN RENSSELAER P. SAXE, OF BALTIMORE, MARYLAND.

REINFORCED-CONCRETE BUILDING CONSTRUCTION.

Application filed May 22, 1922. Serial No. 562,638

The general object of this invention is to improve reenforced concrete buildings while lessening their cost. Non-wood buildings often have metal frames the members of which are provided with an incombustible covering sometimes of concrete. Another class of such buildings has concrete walls containing reinforcing metal elements. In the one class, the entire frame may be erected as a frame of metal, only, or it may be erected in parts extending from foundation to roof, or extending to the height of one or more stories. In the other class, metal and cement elements must be built up together, and much of the metal is embedded in the concrete by which it is held, but its parts are not all directly connected, many being held only by the concrete.

This invention combines advantages of both types and in combining, the construction is such as to secure a great number of advantages. The metal members are directly connected and, as in metal frame buildings, may be assembled to form a structure of practically any desired horizontal or vertical dimensions, quite independently of the concrete, which may if desired be entirely omitted until the whole reenforcing structure is completed. This metal reenforcement preferably has no rolled I-beams or girders, but has its columns of that cross-section. The beams are compound and made up, principally, of flat and angle stock, such as is kept on hand in many sizes by the ordinary dealers in such goods. It follows that the construction of these parts of any building, large or small, heavy or light, is what is sometimes called "rational", that is in close accord in each part with calculated strains to be borne by such parts, which are selected so as to give proper strength.

Reinforcement of this character is readily made capable of carrying, with a very large factor of safety, its own weight, the weight of other construction material, apparatus and concrete forms, and even the weight of a concrete roof, all before any concrete is used below the roof. Provision is made for enabling the reenforcing frame, without cement or concrete, to resist wind pressure in any direction.

In the drawings:—

Figure 1 is a diagrammatic plan of the steel reenforcement of a building made in accordance with this invention. 55

Fig. 2 is a detail of the reinforcement for a wall beam indicated at "2", Fig. 1.

Fig. 3 shows the reinforcement for an interior beam, indicated at "3-3", Fig. 1. 60

Fig. 4 is a detail of my reinforcement for a small interior beam indicated at "4", Fig. 1.

Figs. 5, 6 and 7 are sections on the lines 5—5, 6—6, and 7—7, respectively, of Fig. 2, concrete being added.

Figs. 8 and 9 are sections on the lines 8-8 and 9-9, respectively, of Fig. 3.

Fig. 10 is a section on the line 10-10,
Fig. 4. 70

Fig. 1 represents any ordinary form of building and in this instance shows merely the relative location of parts and constructions hereinafter mentioned. In this figure, 10, 10' represent columns spaced around the outer lines of the building and at desired points within that line, and 11, 11 represent horizontal elements, or beams, extending from column to column or between other beams. Fig. 2 shows in elevation corresponding parts of columns 10, 10', Fig. 1, and of a compound beam 13 connecting them. This beam has an upper angle member 14, an oppositely turned lower angle member 15 having its vertical member offset from the plane of the corresponding member of 14 to a distance equal to the thickness of vertical bars or shear plates 16, each bent above to form a flange 16' in the plane of the upper flange of 14, and riveted to both 14 and 15 each of which has its ends secured by rivets 17 to a broad vertical plate 18 extending vertically materially beyond the beam and strongly secured to the

adjacent column 10, the plate on the right being riveted to the central web of the column while that on the left is riveted to one of the flanges of the corresponding column which is of heavy I-beam shape. These plates 18 are preferably used where any beam meets a column of the outer wall or of any heavy partition, and the entire frame is thus rigidly braced without showing braces when the frame is encased in con-

crete. Alongside the plates 18 the ends of a truss bar 19 are riveted to the horizontal flange of the member 14 and extended obliquely downward to the plane of the like flange of the member 15 along which it passes, under the ends of laterally flanged struts 16", Fig. 6, analogous to the members 16. It may be here noted that this beam is light, extremely strong, and made up of readily handled steel plates and angles which are always in stock, being as staple as nails, and that the construction gives an unusually stiff column and beam connection. As the construction is duplicated over and over in going around the building and in crossing the same, no concrete is needed to make the structure as a whole resist wind and other lateral strains in any direction. The construction of interior beams is slightly different and Fig. 3 shows an interior beam without the broad stiffening plate 18 of Fig. 1, other members being substantially duplicated in forming a heavy beam capable of supporting safely the ends of smaller lateral beams. There are in this beam two oppositely turned members 14, two oppositely turned members 15 and two truss bars 19, as seen in Fig. 8, vertical members 16", from which project lateral flanges 16"" to support upper and lower angle bars 14', 15' of smaller transverse beams, as seen in Fig. 8, which is a section at 8—8, Fig. 3. Where there is no transverse small beam, it is preferred to connect the members 14 and members 15 by U-shaped tie members 20, 20', as seen in Fig. 9. The small transverse beam of Figs. 4, 10 has members 14', 15', etc., corresponding to 14, 15, 16, 16', 19 of Figs. 1, 6, 7.

The steel frame thus far set forth is capable of self support and of carrying relatively moderate weight, and even supporting a heavy roof as well as the forms for concrete, the un-set concrete, and the temporary construction material. When this metal structure is ready, thin wood forms for concrete are secured to the framework in any convenient way, usually largely by wires such as 21, Fig. 6 and the whole frame being thus encased in concrete, the structure is strong enough, when the concrete is fully set and the forms are removed, to carry with a large factor of safety, any load suitable for such a building.

It is to be observed that no heavy girders and no one piece I-beams are employed. The columns alone are of I-beam cross section with the flanges very wide so that the cross section is of I form. With the aid of proper appliances, these, the only heavy members, are readily erected at the outset, and thereafter the light members are assembled and united rapidly, at a low cost. As the thin concrete forms are all placed about

strong metal members already securely fixed 65 and are tied to those members at as short intervals as may be desired, there is a great saving in lumber, in time, and the labor of putting the lumber in place, no "shores" or extraneous supports of any kind being used. 70

Obviously, the time required for erecting is far less than in ordinary construction, partly because there is no waiting for concrete to set, partly because the heavy columns are erected by proper appliances 75 before other parts are in the way, the subsequent work consisting in adding light, easily handled members and riveting them in place, and partly because shores are eliminated and very light lumber is quickly wired 80 in place to serve as concrete forms.

Evidently, too, from the great variety of angle and plate steel usually carried in stock, members are quickly selected and afford any desired strength of beam that 85 calculation shows to be needed, and for sustaining very heavy loads the main members of any beam may be duplicated, doubling the strength. 90

What I claim is:—

1. A self supporting and load sustaining beam for reenforced concrete construction, consisting of relatively light parallel tension and compression chord members, a plurality of transverse strut members and a tension 95 truss bar resting against the lower ends of said strut members and terminally attached to said parallel compression chord member.

2. A concrete reenforcing beam of rolled steel adapted to support a load during construction having light upper and lower rectilinear tension and compression chord members extending from end to end of the beam, short transverse, spaced members connecting the members first mentioned, and a tension truss bar centrally resting against the lower ends of the short members and terminally attached to the compression chord member above; the several members being rigidly connected. 100

3. In a reenforced concrete building, column connecting beams consisting of relatively light parallel tension and compression chord members, a plurality of transverse strut members and a tension truss bar centrally resting against the lower ends of said transverse members and terminally secured to said compression chord, said beams being adapted for connection with columns to form a self sustaining and load supporting structure. 110

4. A self supporting and load sustaining beam for reenforced concrete construction, consisting of parallel tension and compression chord members, a plurality of transverse strut members, a tension truss bar resting against the lower ends of said strut members and terminally attached to said 125

compression chord member, and a plurality of transverse shear members connecting said chord members.

5. A concrete reenforcing beam of light rolled metal consisting of upper and lower structural shapes terminally attached to long gusset plates and centrally connected by vertical strut members and a tension bar terminally attached to said upper structural shape and centrally pressing against the lower ends of said strut members.

6. In a reinforced concrete building self sustaining and load supporting column reinforcement, column connecting beams consisting of parallel tension and compression chord members, a plurality of transverse strut members and a tension truss bar centrally resting against the lower ends of said

transverse members and terminally secured to said compression chord, said beams and column reenforcement being rigidly connected to form a self sustaining and load supporting structure.

7. A reenforcing beam of light rolled metal consisting of upper and lower oppositely turned angle bars riveted terminally to opposite faces of long gusset plates and centrally connected by short vertical members each having a lateral flange, and a tension bar terminally riveted to the horizontal flange of the upper angle bar and centrally pressing against the lower ends of said lateral flanges.

In testimony whereof I hereunto affix my signature.

VAN RENSSELAER P. SAXE.
